UNITED STATES PATENT OFFICE

2,084,373

PEDAL CONSTRUCTION

Bert J. Anderson, Hammond, Ind.

Application April 20, 1935, Serial No. 17,436

11 Claims. (Cl. 208—70)

This invention relates to an improvement in a velocipede pedal construction and has for one of its chief objects the economical construction of an article consisting of a few parts which may be 5 easily assembled.

Another important object of the pedal of this invention resides in the construction of the body itself which is preferably of extruded rubber composition having a plurality of longitudinal 10 openings therein.

A still further important object of the invention resides in the fact that the central portion of each working surface is corrugated and that the walls of this portion of the body are of 15 greater thickness than are the walls at either end.

Still another and further important object of the pedal here set forth resides in the means for preventing rotation of the body independent of 20 the sides.

A further important object of this invention resides in the bushing means for securing the plates to the body.

An additional object of importance resides in 25 the provision of means for preventing the plates from squeezing or otherwise distorting the resilient body of the pedal.

Additional objects of importance and advantage, some of which are hereinafter set forth, will 30 be apparent from the disclosures made in the accompanying drawing and the following specification.

In the drawing:

Figure 1 is a top plan view of the pedal of this 35 invention.

Figure 2 is a side elevation taken on the line 2—2 of Figure 1, looking in the direction indicated by the arrows.

Figure 3 is an elevation taken from the opposite 40 end of the pedal.

Figure 4 is an elevation of the plate showing the relative positions and shapes of the indentations and aperture therein.

Figure 5 is an elevation of the body of the 45 pedal and shows the relative position and shapes of the openings therein.

Figure 6 is a sectional view taken on the line 6—6 of Figure 4.

Figure 7 is a top plan view of the apertured 50 cap.

Figure 8 is a sectional view of the cap taken on the line 8—8 of Figure 7.

Figure 9 is a front elevation of the castellated bushing.

Figure 10 is a plan view of a portion of a blank 55 used for forming the bushing.

Figure 11 is a vertical sectional view taken on the line 11—11 of Figure 2, looking in the direction indicated by the arrows, and also shows the washer and upset portion of the crank shaft.

As shown in the drawing:

The reference numeral 10 indicates in a general way the body of the pedal of this invention which is substantially oval in cross section and is preferably constructed of a resilient rubber composition. The body 10 is preferably extruded in long strips which may be cut into any length, depending on the width of the pedal desired. 5

Penetrating the center of the body 10 is an aperture 12 which follows the longitudinal axis of 10 the strip. When cut into pedal lengths this aperture is used for a bushing receiving opening.

Positioned on each side of and parallel to the aperture 12 are apertures 14 and 16. These apertures 14 and 16 serve the purpose of requiring 15 less stock in the manufacture of the article, providing greater resiliency at the front and rear edge of the body, and also a securing means for keeping end plates in alignment. The aperture 16 is substantially triangular in section and the 20 aperture 14 is semi-circular as the surfaces of both conform in contour to the adjacent outer surface of the body 10, as is best shown in Figure 5. The portion of the body directly above and below the aperture 12 is comparatively thick, as 25 is best shown in Figure 5, to resist wear.

Positioned on each end of the body 10 is an apertured end plate 18 which has depressions 20, and 22, adapted to be inserted into the apertures 14 and 16, respectively. The aperture 24 is 30 adapted to receive the end of a castellated bushing.

Extending through the aperture 12 is a bushing 26 each end of which is castellated as is clearly shown in Figure 9. This bushing is preferably stamped from sheet metal in flat form, as 35 is best shown by the reference numeral 28, in Figure 10, and is then rolled into cylindrical formation. Each end of the bushing 26 protrudes from the body 10, and is adapted to receive an 40 end plate which is secured in position by the portion 30, of the end plate 18 coming into contact with the portion 32 of the edge of the bushing, which prevents inward movement, and by crimping the portion 34 of the bushing against 45 the outer surface of the plate 18, as is best shown in Figures 2 and 11, to prevent outward movement.

A crank shaft 36 adapted to receive the pedal has an upset 38 on opposed sides thereof and a 50 restricted end portion. In mounting the pedal on the shaft 36 for use, a washer 40 is slipped onto the shaft and against the upsets 38. The shaft is then inserted through the bushing 26. Positioned on the restricted end of the shaft with 55 said restricted portion passing therethrough is an apertured cap 42. The end of the shaft is then headed 44 to hold the pedal in operable position on the shaft.

It will be apparent from the foregoing that 60

herein is provided a semi-solid enclosed pedal which may be quickly and economically manufactured and which may be secured to the crank shaft of a velocipede without the aid of nuts or bolts or special tools. It will be further apparent that bolts and nuts or their equivalents are not required in the assembly of the various parts.

Furthermore, because of the absence of rivets or bolts adjacent the ends of the plates, streamlining can be carried out and still maintain a symmetrical and balanced pedal. This makes the pedal highly desirable for use with the new streamlined velocipedes.

I am aware that many changes may be made and numerous details of construction varied throughout a wide range without departing from the principles of this invention, and I, therefore, do not purpose limiting the patent granted hereon otherwise than as necessitated by the prior art.

I claim as my invention:

1. A velocipede pedal having a resilient body with apertures therein, an apertured plate on each side of said body, indented means on each plate co-acting with the apertures in said body to prevent rotation of said body relative to said plates, a castellated bushing positioned in one of the apertures in said body, portions of said bushing extending through said plates and adapted to be crimped thereagainst, portions of said bushing adapted to abut against the inner surfaces of said plates, and means for rotatively securing said pedal to a crank shaft.

2. In a velocipede pedal having a resilient body substantially oval in cross section, apertured members secured to each end of said body, means formed of portions of said members and co-acting with portions of said body for maintaining said body and said members in alignment, and a castellated tubular member extending from one of said apertured members through said body to the other apertured member.

3. In a velocipede pedal having a resilient body substantially oval in cross section and with apertures therein, said apertures comprising a centrally located bushing receiving opening and an aperture on each side of said centrally located bushing receiving opening, a bushing positioned in said centrally located aperture with the ends of said bushing extending therebeyond, an apertured substantially oval shaped plate positioned on each extending bushing end, portions of said plates being indented, said indentations being inserted in the apertures on each side of said centrally located bushing opening, and means for rotatively securing said pedal to a crank shaft.

4. A velocipede pedal, a body having a plurality of apertures extending from end to end thereof, an apertured plate positioned on each end of said body, indentations in each plate entering corresponding apertures in said body, and a bushing positioned in one of said body apertures and extending through said plates and having the ends thereof turned outwardly.

5. A velocipede pedal, a body having a plurality of apertures extending from end to end thereof, an apertured plate positioned on each end of said body, indentations in each plate entering corresponding apertures in said body, a bushing positioned in one of said body apertures and extending through said plates and having the ends

thereof turned outwardly, and means for securing said pedal in operable position on a crank shaft.

6. A velocipede pedal, a body having a plurality of apertures extending from end to end thereof, an apertured plate positioned on each end of said body, indentations in each plate entering corresponding apertures in said body, a bushing positioned in one of said body apertures and having the ends thereof turned outwardly, and means for securing said pedal in operable position on a crank shaft, said means comprising a shaft having an upset on opposed sides thereof and a restricted end, a washer surrounding said shaft and in association with said upsets and said outwardly turned ends of said bushing, an apertured cap positioned over said outwardly turned ends on the opposite ends of said bushing and on the restricted end of the shaft extending through said apertured cap and secured thereto.

7. In a pedal substantially oval in cross section a pair of apertured end plates substantially oval in plan formation, a tubular member having castellated ends secured in said apertured end plates, portions of the ends of said tubular member being in abutment with the inner surface of said plates and portions of said ends extending through said plate and being crimped against the outer surface thereof.

8. In a velocipede pedal, a body, an indented side plate on each side of said body, said plate having an aperture therein, certain portions of the periphery of said aperture being on an arc of a different diameter than certain other portions thereof, means for securing each plate against rotation relative to each other, and means for operatively securing the pedal to a crank shaft.

9. In a velocipede pedal having an apertured body substantially pear-shaped in cross section, a pair of apertured end plates substantially pear-shaped in plan formation positioned one on each end of said body, a tubular member positioned within said apertured body, each end of said tubular member extending beyond said body and through the aperture in an end plate, and means formed of portions of each plate for maintaining said end plates and said body in aligned relation.

10. In a velocipede pedal having an apertured body substantially oval in cross section, a pair of apertured end plates substantially oval in plan formation positioned one on each end of said body, a tubular member positioned within said apertured body, each end of said tubular member extending beyond said body and through the aperture in an end plate, and means for maintaining said end plates and said body in aligned relation, said means including each end of the tubular member being crimped against one of said end plates.

11. In a velocipede pedal, an apertured pear-shaped body, an apertured pear-shaped plate on each end of said body, said apertures being in alignment, a bushing positioned within said aligned apertures, and means formed of portions of each plate which cooperate with portions of the body for maintaining said body and apertured plates in aligned relation.

BERT J. ANDERSON.
